[57] CLAIM

The ornamental design for cosmetic case, as shown and described.

DESCRIPTION

FIG. 1 is a perspective view of a cosmetic case, showing my new design;

FIG. 2 is a front view thereof;

FIG. 3 is a top view thereof;

FIG. 4 is a bottom view thereof;

FIG. 5 is a rear view thereof;

FIG. 6 is a side view thereof;

FIG. 7 is a perspective view of an alternative embodiment of my new design;

FIG. 8 is a front view thereof;

FIG. 9 is a side view thereof;

FIG. 10 is a top view thereof;

FIG. 11 is a perspective view of a second alternative embodiment of my new design;

FIG. 12 is a perspective view of the open case;

FIG. 13 is a front view thereof;

FIG. 14 is a side view thereof;

FIG. 15 is a top view thereof.
